UNITED STATES PATENT OFFICE.

ELIZABETH HARMEL, OF MOUNT CLEMENS, MICHIGAN.

CURTAIN-POLE.

1,002,840.

Specification of Letters Patent. Patented Sept. 12, 1911.

Application filed March 29, 1910. Serial No. 552,153.

To all whom it may concern:

Be it known that I, ELIZABETH HARMEL, a citizen of the United States, and a resident of Mount Clemens, in the county of 5 Macomb and State of Michigan, have invented certain new and useful Improvements in Curtain-Poles, of which the following is a specification, reference being had to the accompanying drawings.

10 This invention relates to certain new and useful improvements in curtain poles, and comprises a slidably held swinging pole, arranged to receive a curtain, screen or other drapery.

15 The primary object of my invention, is to provide a neat, readily adjustable curtain pole, carrying a hanging fabric, screen or curtain, which can be swung away from the door or window opening.

20 A further object is to provide a swinging curtain pole arranged so that the pole may be lengthened or shortened.

With these and other objects in view the present invention consists in the combination 25 and arrangement of parts as will be herein-after more fully described and particularly pointed out in the appended claim, it being understood that changes in the specific structure shown and described may be made 30 within the scope of the claim, without departing from the spirit of the invention.

In the drawings forming a part of this specification and in which like numerals of reference indicate similar parts, Figure 1, 35 shows an elevational view of a swinging curtain pole embodying my invention with a portion of the pole broken away. Fig. 2, is a view disclosing the carrying tube in section, while Fig. 3, shows a detached detail 40 of the terminal collar as used in my invention.

In homes and other buildings, where curtains or other hanging fabric screens are used, to close a door-way or an alcove, or 45 where draperies are used for ornamental purposes, it is highly desirable that the carrying pole should be so supported, that the curtain, screens or fabric may be swung out, so that the door or window opening may be 50 entirely uncovered, permitting a re-arrangement of the fabric, as well as permitting the door or window to be cleaned without having to dis-arrange the fabric or curtain.

In carrying out the object of my invention 55 I use an ornamental elongated base 1, of wood or any other suitable material which

is arranged to be secured to the door or window frame, A as is shown in Fig. 1, in a vertical position. Secured to the ends of this base, by means of screws, are the apertured supporting ears 2 and 7. Revolubly held within the ears 2 and 7, is the post 5, in the form of a rod, having its ends threaded and being provided near the upper end with a stop shoulder 6. Held to the 65 ends of the post 5, are the ornamental nuts 4 and 8. Held upon the post 5, between the stop shoulder 6 and the supporting ear 2 is the block 3, from which extends the boss 1'. Secured to this boss 1', is the supporting 70 tube 10 having a thread opening near its outer end and which carries the collar 11, having a threaded aperture arranged to receive a pointed set screw 16 having the ornamental operating head 15, as shown in 75 Fig. 3. The screw 16, passes through the opening within the tube, as shown in Fig. 2.

The tube 10 carries the collar 11', from which extends a pin 5', held to the curved brace 9, which brace at one end engages the 80 post 5, as shown in Figs. 1 and 2, while the upper end of the brace 9 has an opening arranged to receive the screw 16, as clearly disclosed in Fig. 2. Ornamental spools 12 are interposed between the tube and the 85 brace 9. As shown, the screw 16 passes through the tube 10.

Slidably held within the tube 10, is a suitable curtain pole 14, which is secured by means of the screw 16, which has its end 90 pointed, as shown in Fig. 3, so as to partly pierce the pole 14, and firmly hold the same against displacement within the socket forming tube 10.

Suitable curtain rings 13, are slidably 95 held upon the tube 10, as well as on the curtain pole 14, to properly hold the curtain or other draperies.

In Fig. 1, is shown a portion of a curtain closing a door opening. Now should it be 100 required to entirely uncover the door opening, it would simply be necessary to swing the pole 14 outward and against the wall. The length of the pole 14 can be nicely adjusted. The adjustment of the base 1, to the supporting member is effected in any 105 suitable workmanlike manner, and by means of the screw 16, displacement of the curtain pole 14 is prevented.

A swinging curtain pole constructed according to my invention, is neat, slightly and inexpensive in construction and both dura- 110

ble and efficient in operation, and the pole adjustments can be made with ease, accuracy and despatch.

Having thus described my said invention what I claim as new, and desire to secure by United States Letters Patent is:—

In a device of the character described, the combination with a base, of two apertured supporting ears secured to the ends of said base, a rod having a stop shoulder revolvably held within said apertures, a block having a boss held upon said rod between said shoulder and one of said ears, a tube secured to said boss said tube having a threaded

opening near its outer end, a set screw within said opening, a curtain pole slidably held within said tube and engaged by said set screw, and a brace bar having one end secured to said rod the other end being engaged by said set screw to secure said brace to said tube, as and for the purpose set forth.

In testimony whereof I affix my signature, in presence of two witnesses.

ELIZABETH HARMEL.
